UNITED STATES PATENT OFFICE.

MARTIN J. HEALY, OF CHICAGO, ILLINOIS, ASSIGNOR TO VICTORY MANUFACTURING COMPANY, OF CHICAGO, ILLINOIS, A CORPORATION OF ILLINOIS.

DESIGN FOR A MEMORIAL-TABLET.

54,414.

Specification for Design.

Patented Feb. 10, 1920.

Application filed December 16, 1918. Serial No. 267,059. Term of patent 7 years.

To all whom it may concern:

Be it known that I, MARTIN J. HEALY, a citizen of the United States, residing at Chicago, in the county of Cook and State of Illinois, have invented a new, original, and ornamental Design for Memorial-Tablets, and of which the following is a specification, reference being made to the drawings forming a part thereof.

The figure in the drawing illustrates a face view of my new design for memorial tablet.

I claim:

The ornamental design for a memorial tablet as shown.

MARTIN J. HEALY.
